Attorney

UNITED STATES PATENT OFFICE.

MELVIN T. HARMON, OF PRICE, UTAH.

RECORD HOLDING AND DISPLAYING FRAME FOR TOMBSTONES, MONUMENTS, ETC.

Application filed December 1, 1924. Serial No. 753,319.

To all whom it may concern:

Be it known that I, MELVIN T. HARMON, a citizen of the United States, residing at Price, in the county of Carbon and State of Utah, have invented certain new and useful Improvements in a Record Holding and Displaying Frame for Tombstones, Monuments, Etc., of which the following is a specification.

10 This invention relates generally to tombstones, monuments, grave markers, etc. and has more particular reference to a means whereby records representative of the person or persons for whom the monument, etc. 15 was erected may be maintained and displayed.

The primary object of an invention of this character is to provide such means whereby it will not be necessary to carve the record 20 directly into the monument, etc. but wherein in the record may be painted, engraved or the like onto a suitable member which is maintained in display within a suitable pocket formed in the monument, etc.

25 A further and important object is to provide a record holding and displaying means for monuments wherein the same may at all times be readily viewed and wherein the entrance of moisture, dirt or the like 30 will be prevented, due to the particular construction of the present means.

A further object is to provide a record holding and displaying means whereby the same may be readily removed from or associated with the monument whenever desired.

With the foregoing and other objects in view, as the nature of the invention will be better understood, the same comprises the novel form, combination and arrangement of parts hereinafter more fully described, shown in the accompanying drawing and claimed.

In the drawing, wherein like reference characters indicate corresponding parts 45 throughout both of the views:

Figure 1 is a front elevational view of a somewhat conventional form of tombstone equipped with my novel record holding and displaying means, and

50 Figure 2 is an enlarged detail vertical sectional view thereof.

Now having particular reference to the drawing, 5 indicates the conventional form of tombstone constructed preferably of a

plastic composition, it being however understood that I do not wish to be limited to the application of my device to a tombstone, monument, or the like of any particular construction or material, insomuch as in the future practice of my invention, the same 60 may be associated with monuments, grave markers, etc. of marble, wood, or other material.

In the present instance wherein the record maintaining and display means is shown as 65 associated with a tombstone of plastic construction, it will be necessary that the major portion of the means be associated with the tombstone during the molding of the same. The construction per se embodies the provision of a generally pan shaped sheet or cast metal frame 6 that is molded within the flat face of the tombstone, the edges of the inner closed end of the pan shaped frame being suitably flanged as at 7 for providing 70 an interlocking feature between the frame and the tombstone as clearly shown in Figure 2.

Within the inner end of the frame adjacent the rear wall thereof is a rectangular 80 shaped frame 8, the four corners and sides of which are formed with bendable sheet metal strips 9 in order to maintain in association with the frame a glass panel 10, upon the rear surface of which is painted or 85 otherwise suitably marked the records of the person represented by the stone. Rearwardly of this glass is a cushioning strip 11 of cardboard or felt, and if desired, may be disposed between the glass and cushion a 90 strip of material upon which ornamental designs are placed for beautifying the same, the cardboard or felt immediately protecting the inscription, record, etc. from moisture and dust.

95 Adjacent the front open end of the pan shaped frame 6, the same is channeled as at 12 within which the edges of a glass window 13 rests. This window 13 is maintained within the channel through the medium of a rectangular shaped frame 14 that is also disposed within the channel 12 forward of the window 13 the same being maintained in position through the medium of bolt and nut connections 15. These nuts of the connections are embedded within the tombstone 100 5 during the molding thereof and the bolts pass through openings in the frame 14 as

clearly shown in Figure 2, in such a manner as to seal the frame 14 tightly to the pan shaped frame 6, preventing ingress of moisture and dust.

- 5 The material forming the frame 6 at a point beyond the channel 12 is flared outwardly for providing a skirt 16 that has close contact with the material forming the stone and at the edge of this skirt the material is so shaped as to provide a channel 17, the upper edge of which extends rearwardly into the material forming the stone so as to prevent moisture passing between the frame and material forming the stone.
- 10 15 It will thus be seen that I have provided a highly novel and efficient form of record retaining and displaying frame for tombstones, monuments, and the like and one wherein the record may be readily removed from the frame for addition purposes, and one wherein the record sheet may be readily viewed by persons passing the monument or

the construction, the said record sheet being at the same time fully protected from moisture and dust.

25

Minor changes may be made in the invention without departing from the spirit and scope of the appended claim.

Having thus described the invention, what I claim as new and desire to secure by Letters Patent is:—

20

In combination with a monument, a relatively pan-shaped body embedded within one face of the monument and including an inner wall and side walls, said inner wall being bent over upon itself at its edges and said bent over portions merging into the side walls, a transparent closure for the pan-shaped body, nuts embedded in to the monument, and bolts for engaging into the nuts 35 and holding the transparency in place.

35

In testimony whereof I affix my signature.

MELVIN T. HARMON.
